W. H. NICHOLSON

GRAB

Filed Feb. 18, 1924

INVENTOR.
W. H. Nicholson
BY George W. Webster
ATTORNEY.

UNITED STATES PATENT OFFICE.

WILLIAM H. NICHOLSON, OF TAFT, CALIFORNIA.

GRAB.

Application filed February 18, 1924. Serial No. 693,652.

To all whom it may concern:

Be it known that I, WILLIAM H. NICHOLSON, a citizen of the United States, residing at Taft, county of Kern, State of California, 5 have invented certain new and useful Improvements in Grabs; and I do declare the following to be a full, clear, and exact description of the same, reference being had to the accompanying drawings, and to the 10 characters of reference marked thereon, which form a part of this application.

This invention relates to improvements in that class of devices known as fishing tools, used in connection with well drilling operations, and particularly to that type of fishing tool commonly known as a grab, used 15 particularly to catch and grasp broken fish-tail bits and similar articles lost in the well.

20 The principal object of my invention is to provide a tool of this character so constructed that the article being fished for will be automatically engaged and grasped with a grip whose holding force increases with 25 an increase of resisting pressure thereagainst.

Another object is to arrange or mount the 30 actual grabs or gripping members in such a manner that with any spread or contraction they move parallel to each other, so that a flat surface being gripped is engaged over the full length of the grabs with equal force.

A further object is to mount the grabs 35 in such a manner that no interference with a free flow of flushing water to a point below the tool is had, regardless of the setting of the grabs relative to each other.

40 A further object of the invention is to produce a simple and inexpensive device and yet one which will be exceedingly effective for the purposes for which it is designed.

These objects I accomplish by means of 45 such structure and relative arrangement of parts as will fully appear by a perusal of the following specification and claims.

In the drawings similar characters of reference indicate corresponding parts in the several views:

50 Fig. 1 is an exterior side elevation of the device.

Fig. 2 is a front elevation of the same, half in section.

Figs. 3 and 4 are cross sections on the lines 3—3 and 4—4 respectively of Fig. 2. 55

Referring now more particularly to the characters of reference on the drawings, the numeral 1 denotes what may be termed the shank of the tool, threaded at its upper end as at 2 for connection to a standard rod-coupling. The lower end of said shank is somewhat enlarged and is tapped as at 3 for connection to the upper end of a head 4 on which the grabs are mounted.

This head is formed with a downwardly 65 extending wedge or V shaped member 5, symmetrically disposed relative to the longitudinal axis of the tool.

The opposite side faces of the member 5 are provided with guide ribs or projections 6 located adjacent and parallel to the sloping edges of said member, which serve as guides and supports for the grooved heads 7 of the grabs 8.

These grabs are rigid members depending 75 below the member 5 a certain distance and having oppositely and transversely disposed teeth 9 cut in their adjacent faces in vertical and transverse parallel alinement, the upper faces of the teeth lying in substantially horizontal planes. From the lowermost of the teeth, to the lower extremity of the grabs, the adjacent faces of the latter are cut with a diverging flare or slope as 80 at 10.

The grabs are normally held adjacent the lower end of the head member 5, and forced 85 to move at all times in unison, by means of a crosshead 11 resting on the grab-heads 7. This crosshead is vertically slidable in a transverse slot 12 cut in the head 4 and extending down into the member 5 for a certain distance.

Fixed on the crosshead 11 centrally thereof and projecting thereabove is a stem 13, 95 slidable in a suitable recess 14 provided in the head 4, a spring 15 mounted in the shank 1 above the stem bearing down thereon. The stem is of sufficient length so that it forms a good guide and bearing member for the crosshead, positively preventing any lateral tipping of the latter.

The shanks, stem and member 5 are axially drilled throughout their entire length as at 16 to provide an unobstructed water passage from one end of the tool to the other.

5 Various methods of construction of the members 4 and 5, and mounting of the grabs 8 on the latter, may be employed to enable the grabs to be assembled and removed when necessary. In the present case, I have shown
10 the guide members 6 on the wedge member 5 as terminating short of the lower end thereof to enable the grab-heads 7 to be individually slid down and off their supporting member 5. To normally prevent such movement, a removable pin 17 or similar member is secured in the member 5 just above the rib-ends, against which pin the lower ends of the grab-heads 7 abut when in their lowermost positions.

20 In operation, the tool is lowered down the well, until the piece being fished for is engaged by and centralized between the grabs by the flares 10 at the lower ends of the same, water being forced through the central bore 25 16 to flush out the well-bore about the broken piece and clear the latter of all sand, mud, etc., in which it may have been buried.

A sharp downward thrust is then given to the tool causing the grabs to be spread apart
30 and the broken piece to pass up therebetween. Since the opposite guide ribs 6 of the wedge shaped member are symmetrically disposed relative to the axis of the tool, the grabs must move so as to maintain their parallel alinement relative to each other and to a vertical plane. Also on account of the
35 slideable but rigidly supported crosshead 11, one grab cannot move without the other, and therefore both grabs will move to the same extent.

40 A flat piece being forced up between the grabs will therefore be engaged on its opposite sides and throughout its height and width by the teeth 9, insuring a rigid grip on the piece.

45 Then when the tool is raised, the grabs, owing to the converging guides on which they are mounted and to the spring 15 acting through the crosshead 11 to force the grabs downwardly, will automatically tend to move toward each other and into firm gripping engagement with the piece therebetween.

50 There being no connecting member between the grabs below the member 5, there is nothing to obstruct the flow of water from the bore 16 and interfere with a good flushing action.

55 From the foregoing description it will be readily seen that I have produced such a device as substantially fulfills the objects of the invention as set forth herein.

60 While this specification sets forth in detail the present and preferred construction of the device, still in practice such deviations from such detail may be resorted to as do not form

a departure from the spirit of the invention, as defined by the appended claims.

Having thus described my invention what I claim as new and useful and desire to secure by Letters Patent is:

70 1. A fishing tool comprising a shank, a V shaped member at the lower end thereof and depending therebelow, and opposed grabs depending from said V shaped member and mounted thereon for sliding movement in planes parallel to the side edges of the V shaped member.

75 2. A fishing tool comprising a shank, a V shaped member at the lower end thereof and depending therebelow, and opposed grabs depending from said V shaped member and mounted thereon for sliding movement in planes parallel to the side edges of the V shaped member, and means whereby said grabs when acted on will move in unison and to the same extent.

80 3. A fishing tool comprising a shank, a V shaped member at the lower end thereof and depending therebelow, and opposed grabs depending from said V shaped member and mounted thereon for sliding movement in planes parallel to the side edges of the V shaped member, and a crosshead bearing on top of the grabs and slidably mounted for vertical movement in the shank.

85 4. A fishing tool comprising a shank, opposed and separate grabs depending from the lower end thereof, and guide and supporting means for the upper ends of said grabs disposed therebetween and depending from the shank, there being an unobstructed opening between the grabs from the lower end of the supporting means downwardly.

90 5. A fishing tool comprising a shank, opposed grabs depending from the lower end thereof, and guide and supporting means for the upper ends of said grabs disposed therebetween and depending from the shank, said guide means being arranged to allow the grabs to move up and down in diverging and converging relation respectively while maintaining a parallel relationship to each other.

95 6. A fishing tool comprising a shank, a V shaped member at the lower end thereof and depending therebelow, and opposed grabs depending from and both supported and guided by said member for upward diverging and downward converging movement.

100 7. A fishing tool comprising a shank, a V shaped member at the lower end thereof and depending therebelow, and opposed grabs depending from and guided by said member, for upward diverging and downward converging movement, while maintaining the grabs in parallel relationship to each other.

105 8. A fishing tool comprising a shank, grabs mounted at and depending from the lower end thereof and arranged for limited vertical movement, means whereby when the grabs are moved upwardly they will auto-

matically diverge from each other while remaining in parallel relationship to each other, a crosshead independent of the grabs bearing on top of the grabs and slidably mounted for vertical movement in the shank, and spring means in the shank acting to cause a downward pressure on the crosshead.

9. A structure as in claim 8, in which the

shank, grab-movement controlling means, and crosshead are provided with vertical 10 passage means therethrough, whereby to allow of an unobstructed flow of water from one end of the tool to the other.

In testimony whereof I affix my signature.

WILLIAM H. NICHOLSON.
